ABRADING MACHINE

Fred Ricks, Leicester, England, assignor to United
Shoe Machinery Corporation, Paterson, N. J.,
a corporation of New Jersey

Application January 23, 1933, Serial No. 652,967
In Great Britain February 4, 1932

1 Claim. (Cl. 51—166)

This invention relates to abrading machines and is herein illustrated as embodied in a machine for performing various buffing operations upon shoes. These operations on shoes call for considerable care and judgment on the part of the operators performing them and since, in the course of a day's work, an operator may have to handle a very large number of shoes, it is highly desirable that his working conditions should be capable of adjustment to suit his individual needs. In particular, it is desirable, in order to avoid excessive fatigue and to enable the operator to perform the highest quality of work, to maintain the buffing tools at the most convenient level for the individual operator, and the most suitable level for one operator may be considerably different from the most suitable level for a taller or shorter operator.

Accordingly, an object of this invention is to provide a buffing machine having provision for the heightwise adjustment of one or more buffing tools.

In the illustrated construction several abrading tools, namely, a pair of bottom scouring rolls, a shank buffering disk, and a heel breast buffering roll are all mounted upon a bracket having provision for heightwise adjustment. The bracket is pivotally supported upon the machine frame about a horizontal axis, and the several tools are driven from a shaft which is coaxial with the pivotal mounting of the bracket. The coaxial relation between the shaft and the pivotal mounting of the bracket affords an advantage in that it enables the bracket to be adjusted about its pivotal mounting without disturbing the driving connections between the shaft and the abrading tool.

The various features of the invention will be best understood from the following description of the preferred embodiment thereof selected for purposes of illustration and shown in the accompanying drawings, in which,

Fig. 1 is a right hand side elevation of the illustrative machine;

Fig. 2 is a front elevation of the said machine drawn to the same scale as Fig. 1;

Fig. 3 is a detail sectional view showing certain parts seen in Fig. 1 drawn to a larger scale than in Fig. 1; and

Fig. 4 is a plan view drawn to a larger scale than Fig. 1 of the upper portion of the said machine, certain parts at the top of the machine being omitted.

The illustrative machine comprises a base framework 1 mounted upon which is a casting 3 provided at its rear end with two upstanding arms

5 one on each side of the machine. Mounted in each of these arms 5 is a sleeve 6 shown only in Fig. 4 through axial bores in which sleeves passes a horizontal shaft 7 substantially coaxial with the sleeves 6 and extending from left to right of the machine, the bores in the sleeves 6 being of slightly larger diameter than is the shaft 7 and the said shaft being actually supported near either end by ball bearings 8 (see Fig. 4) mounted in arms 10 extending from the casting 3. One of the arms 10 is adjacent to and integral with one of the arms 5, the arm 10 and the arm 5 together constituting, in effect, a bifurcated extension of the casting 3; and the same is true of the other arm 10 and the other arm 5. Journaled in 10 bearings at the foot of the base framework 1 of the machine is a power driven horizontal shaft 9 which carries at its left hand end a pair of fixed and loose pulleys 111 and 113 for engagement with a belt 115 driven from any suitable 15 source of power. Cooperating with the belt 115 is a belt shifter of well-known construction operated by a hand lever 117 for controlling the drive of the shaft 9. Upon the right hand end portion of the shaft 9 is fixed a pulley 11. A considerably smaller pulley 15 is mounted on the shaft 7, and a belt 13 runs over these two pulleys thereby rotating the shaft 7 at a high speed. Above the casting 3 the machine is provided with a large flat bracket 17 (Fig. 4) having at its rear 20 portion two arms 19. Each of the arms 19 has formed in it a bearing, and these bearings engage respectively the sleeves 6 to provide for the bracket 17 a pivotal mounting about the axis of the shaft 7. This arrangement renders the 25 bracket 17 capable of heightwise swinging movement about the axis of the shaft 7. In threaded relation with a short transverse rod or swivel pin 21 (Figs. 3 and 4) rotatably mounted in two upstanding flanges 23 formed on the upper surface of the bracket 17 and substantially centrally situated thereon is a large vertical screw 25 which passes through a hole in the bracket and at its lower end bears against a cup shaped portion 27 of an upstanding rib 29 formed internally in the 30 said casting 3. The arrangement is such that rotation of the screw 25 causes the bracket 17 to turn about the pivot at its rear end and so raises or lowers the front portion of the said bracket. To maintain the bracket 17 securely in adjusted 35 position the said bracket is provided with downwardly extending side portions 31 (Fig. 2) from which project bolts 33 rigidly secured thereto. The bolts pass through arcuate slots 35 (Fig. 1) in the casting 3 and by tightening nuts 37 upon 40

50 55

the ends of the bolts 33 the bracket 17 may be locked in position.

From the front of the bracket 17 there project two short arms 39 (Fig. 4) which carry bearings 40 in which bearings is mounted a bottom scouring roll carrying shaft 41. Two bottom scouring rolls 43, 45 (Fig. 2) are carried on the shaft 41, one roll being normally covered with rough abrasive paper and the other with fine abrasive paper. 5 Towards its right hand end the bottom scouring roll carrying shaft 41 has a pulley 47 secured to it, and a belt 49 passes round this pulley 47 and also round a pulley 51 formed integrally with the pulley 15 on the horizontal shaft 7 already mentioned. The arrangement may conveniently be such that the bottom scouring roll carrying shaft 41 is rotated by the belt 49 at a speed of about 4000 revolutions per minute. 10 It is usual in driving bottom scouring rolls, to reciprocate the rolls through the shaft upon which they are mounted. For this purpose there is provided mechanism comprising an arm 53 bolted to the top surface of the bracket 17 and at the right hand side thereof and extending to 15 the right of the said bracket. At the right hand end of this arm 53 is supported a vertical stud 55 which forms a centrally situated pivot for a lever 57 extending substantially forwardly and rearwardly of the machine. At its rear end this 20 lever 57 is provided with a short vertical stud 59 which carries at its lower end a cam roll 61 which enters a cam groove 60 cut in the extended hub 62 of a pulley 63 carried at near the extreme right hand end of the horizontal shaft 7 and fixed longitudinally on the shaft but capable of rotation 25 relatively to the shaft. A belt 65 runs round the pulley 63 and also round a small pulley 67 on the shaft 9; the arrangement being such that the pulley 63 with the extended hub is driven at a 30 very much slower speed than the shaft 7 upon which it is carried, for example at less than a tenth of the speed. At its forward end the lever 57 is forked and the fork arms pass one above and one below the bottom scouring roll carrying 35 shaft 41. Each fork arm carries a short stud 69, and both studs 69 enter radial holes formed in the periphery of a sleeve 70 (seen only in Fig. 4) which is rotatably mounted on the shaft 41 and prevented from axial movement by the provision 40 of two collars 71 fixed relatively to the shaft 41. These collars 71 are secured to a reduced portion at the right hand end of the shaft 41 by means of nuts 72 in threaded relation with the said shaft 41. Actually the arrangement is such that the 45 sleeve 70 is rotatably carried on a short sleeve (not shown) which serves to space the collars 71. On tightening the nuts 72 the collars 71 are clamped between these nuts and the shoulder on the shaft 41 where the reduced end portion of 50 the shaft 41 begins, but the short sleeve just mentioned prevents the collars 71 binding the sleeve 70 tightly between them. The comparatively slow rotation of the hubbed pulley 63 conveys, through the cam groove in its hub, oscillatory 55 movement to the lever 57 about its central pivot 55 and this in turn communicates a reciprocatory movement to the bottom scouring roll carrying shaft 41, the frequency of this reciprocatory movement being much less than the speed of rotation of the shaft 41. For example while the bottom scouring roll carrying shaft may as already mentioned be rotated at a speed of about 4000 revolutions per minute we have found it convenient to reciprocate it at a frequency of only 60 75 250 reciprocations per minute.

The top and rear surfaces of each of the bottom scouring rolls 43, 45 are covered by pivoted members 73 and 75 respectively which, besides performing a guarding function, also assist in the collection of dust from the said rolls. These members 73 and 75, which thus constitute dust hoods, are pivoted to the front surface of the bracket 17.

To a face 76 (Fig. 4) at the left hand side of the top surface of the bracket 17 is bolted a supporting structure 77 for a shank buffering tool 79 of the disk type and for a frusto-conical abrasive tool 81 of relatively small diameter for operating upon curved surfaces such as are presented by Louis heel breasts. The frusto-conical abrasive tool 81 is mounted at the left hand end of a shaft 83 which rotates in suitable bearings formed in the said supporting structure 77, the shaft 83 being driven by a belt 85 which runs round a pulley 87 at the right hand end of the shaft 83 and also round a pulley 89 on the horizontal shaft 7. This belt 85 passes through a clearance hole 90 (see Fig. 4) cut in the bracket 17. The shank buffering tool 79 is carried at the lower end of a substantially vertical shaft 91 also journaled in the supporting structure 77. The shank buffering tool 79 is positioned above the left hand bottom scouring roll 43. The shaft 91 is also driven from the horizontal shaft 7 by means of a pulley 92 fixed on the horizontal shaft 7 and a belt 93 which runs over two idle pulleys 95. The supporting structure 77 is conveniently constructed so that it has a duct formed in it communicating with the open end of a dust hood 97 located just behind the shank buffering tool 79. The other end 35 of the duct is connected by a flexible conduit 99 to a suitable suction conduit 101 which leads to the intake of an exhaust blower 103 secured upon the frame 1 and driven by a belt 109 from the main shaft 9. The machine is also provided with 40 a dust collecting duct 105 which divides into two branches which open immediately behind each of the bottom scouring rolls 43 and 45, respectively, in order to collect dust formed during the operation of these rolls. The conduit 105 leads to 45 the suction conduit 101, and has a flexible portion to accommodate the up and down adjustments of the bracket 17. Beneath the rolls 43 and 45 and secured to the frame 1 is a dust receptacle or pan 107 having a large opening to receive dust from the work. The dust pan 107 also communicates with the suction conduit 101.

It will be realized that by adjusting the heightwise position of the bracket 17 the position of the buffering and scouring instrumentalities may readily be adjusted to the position most suited to any particular operator. When the operator desires to adjust the heightwise position of the bracket 17 he has merely to loosen the nuts 37 and to rotate the screw 25 (which is provided with a head 99 so shaped that a spanner or like tool may be readily applied thereto, to aid rotation of the screw). The operator can thus adjust the height of the scouring instrumentalities to the position he finds most convenient, a result which as already mentioned hereinbefore is a very desirable one. It will be observed that the driving means already described for the various scouring instrumentalities are so designed and arranged that they are unaffected by heightwise adjustment 70 of the tools. When the operator has suitably adjusted the height of the scouring instrumentalities he will once more tighten up the nuts 37 thereby firmly securing the bracket 17 in adjusted position.

Having described my invention, what I claim as new and desire to secure by Letters Patent of the United States is:

A shoe buffing machine comprising a frame, a pair of bearings supported by said frame, a substantially horizontal shaft journaled in said bearings, a pair of sleeves secured in said frame concentrically with said shaft, the internal diameters of said sleeves being greater than the diameter of said shaft, a bracket pivotally mounted

on said sleeves, a buffing tool carried by said bracket, driving means between said shaft and said buffing tool, a swivel pin mounted in said bracket, a bolt threaded through said swivel pin, and a cupped abutment supported by said frame, said bolt serving to adjust the angular position of said bracket about the axis of said shaft and thereby to determine the level of said buffing tool. 5
